McCall & Pierce Atty's

UNITED STATES PATENT OFFICE

DOUGLAS F. FESLER, OF EVANSTON, ILLINOIS, ASSIGNOR TO ALEMITE CORPORATION, OF CHICAGO, ILLINOIS, A CORPORATION OF DELAWARE

COMPRESSOR

Application filed November 16, 1921, Serial No. 515,460. Renewed July 7, 1930.

My invention relates to improvements in compressors, and is particularly concerned with the provision of a novel compressor adapted to form a part of a well-known lubricating system, comprising a plurality of fittings or nipples to be secured to the various bearings on the machine to be lubricated, and a compressor for supplying lubricant to the fittings, the compressor comprising a discharge conduit having a coupling for successively making sealed connections with said fittings.

10 The objects of my present invention are

First: To provide a compressor by means 15 of which lubricant under exceedingly high pressure can be easily delivered to the fittings;

Second: To provide a compressor of the character described comprising means for 20 rapidly forcing a comparatively large amount of lubricant into a bearing, where the resistance of the bearing is small, but which, at the same time, embodies means for supplying lubricant to the bearings under 25 high pressure where such high pressure is necessary for forcing the lubricant between the surfaces to be lubricated;

Third: To provide a compressor having a discharge conduit which comprises a sealing 30 member and a valve co-acting in a novel manner, and

Fourth: To provide a construction of the character specified which is simple, economical to manufacture, rugged and easy to operate.

Other objects will appear as this description progresses, reference being had to the accompanying drawing, in which

Figure 1 shows my improved compressor 40 in side elevation, and

Figure 2 is a central longitudinal section through the discharge conduit forming a part of my compressor.

In both views, similar reference characters 45 will be used for referring to similar parts.

Referring to the drawing, my improved compressor comprises a low pressure cylinder or barrel 5, one end of which is closed by a suitable cap 6, which can be removed for the 50 purposes of filling the compressor. A screw

threaded plunger rod 7 is threaded through the cap 6, and carries a plunger 8 at its inner end, the outer end of the plunger rod being provided with a handle 9 by means of which it can be rotated. A nipple 10 projects from 55 the closed end 11 of the low pressure cylinder. The construction thus far disclosed is well-known to those skilled in this art, and is purely conventional in character and forms no part of my present invention except as it 60 co-acts with the remaining elements about to be described.

The discharge conduit of my improved compressor comprises a guide tube 12, one end of which is reduced in cross-section and 65 threaded as shown at 13, so that it can be connected with the internally threaded nipple 10. Adjacent its inner end, the guide tube 12 is internally threaded as shown at 15 to receive the externally and internally threaded 70 collar 16. The inner end of the plunger tube 17 is threaded into the bore of the collar 16, so as to support the plunger tube 17 in spaced relation to the walls of the guide tube 12. The inner end of the high pressure tube or 75 cylinder 18 is slidably mounted in the outer end of the guide tube 12, and surrounds the plunger tube 17, as shown in Figure 2. To provide a tight joint between the end of the tube 18 and the plunger tube 17, I provide 80 suitable packing 19, and a follower 20, the outer end of which is provided with slots 21 for receiving a spanner wrench. Preferably, the outer end of the plunger tube 17 is 85 provided with a collar or enlargement 22, which co-acts with the shoulder 23 at the inner end of the tube 18 to limit the outward movement of the tube 18 with respect to the guide tube 12.

A sleeve 24 is threaded upon the outer end 90 of the high pressure tube or cylinder 18. The outer end of the bore of the sleeve is contracted to provide a seat 25 for the flexible gasket or cup leather 26. A valve 27 seats 95 upon the inner side of the flexible gasket 26, and has a short stem 28, which projects through the opening 29 in the gasket 26 for a purpose which will later be referred to. The helical spring 30 positioned between the 100

outer end of the tube 18, and the valve 27 yieldingly holds the latter upon its seat.

I also provide means at the inner end of the discharge conduit for preventing the high pressure developed in the high pressure cylinder or tube 18 from being transmitted to the low pressure cylinder, this means comprising a check valve 31, the inner face of which is provided with a projecting member 32, which, when the valve is seated, extends through the opening in the gasket 33. A helical spring 34 yieldingly holds valve 31 upon its seat. The outer face of the valve 31 is provided with a projection 35 for keeping the adjacent end of the spring centered upon the valve.

Although it is not necessary for the successful operation of my improved compressor, the outer end of the sleeve 24 may, if desired, be provided with bayonet slots 36 for receiving the projecting ends of the pin 37, forming a part of the nipple or fitting 38, so as to make a locked attachment to the fitting. The fitting 38 is of the usual well-known type comprising a non-return valve 40, and a spring 41, seated between it and the pin 37 for yieldingly holding the closure 40 in its closed position.

In using my improved compressor, the outer end of the sleeve 24 is placed over and around the outer end of the nipple 38, as shown in Figure 1, and the operator then rotates the plunger rod 7 by means of a handle 9, thereby causing the plunger 8 to move inwardly in the low pressure barrel or cylinder 5, thus forcing lubricant past the valve 31 into the chamber between the end of the guide tube 12 and the inner end of the plunger tube 17, and from thence through the plunger tube into the high pressure cylinder 18. From the high pressure cylinder 18, the lubricant flows past the valve 27 (which has been raised by the engagement of its stem 28 with the closure 40) and into the fitting 38 and from thence to the bearing. If the resistance to the passage of lubricant into the bearing is so great as to make the turning of the handle 9 difficult, the operator simply pushes upon the handle 9, or the barrel 5, or both, in the direction of the axis of the discharge conduit, whereupon the plunger tube 17 will be forced into the high pressure cylinder or tube 18, and displace lubricant therefrom past the valve 27 through the fitting and into the bearing. It will be noted that the diameter of the plunger tube 17 is comparatively small, so that pressures of a thousand pounds or more per square inch can easily be developed in the high pressure cylinder 18. In making an attachment or connection with a fitting 38, the outer end of the valve stem 28 first makes contact with the closure 40, and because of the greater tension of the spring 30, it causes the closure 40 to open against the tension of the spring 41. The

closure 40, however, has a limited movement, and when it reaches the end of this movement it acts as an abutment for the valve stem 28, so that upon further movement of the sleeve 24 toward the fitting 38 this valve is lifted from its seat upon the gasket 26 but immediately thereafter the gasket 26 comes into contact with the end of the fitting 38 and makes a sealed connection with this fitting. When the plunger in the barrel 5 is operated to force lubricant into the discharge conduit, under pressure, the pressure of the lubricant upon the inner face of the gasket 26 causes it to be forced tightly against the end of the fitting 38 and the greater the pressure, the better the seal between these two members so that there is no opportunity for lubricant to escape through the joint.

After the three members 12, 17 and 18 have been telescoped within each other by exertion of pressure upon the handle of barrel 5, to return them to their former position it is merely necessary to remove the sleeve 24 from the fitting and turn the handle 9 through a couple of rotations, whereupon the pressure of the lubricant against the valve 26 will cause the high pressure cylinder to move outwardly to the position shown in Figure 2.

While I have described the details of construction of a preferred embodiment of my invention, it is to be clearly understood that my invention is not limited to these details but is capable of other adaptations and modifications within the scope of the appended claims.

Having thus described my invention, what I claim is:

1. A compressor comprising a low pressure cylinder having a discharge conduit comprising, a guide tube communicating with said low pressure cylinder, a plunger tube mounted within said guide tube, and communicating with the interior thereof, the outer end of said plunger tube being freely supported in spaced relation to the walls of said guide tube, a high pressure cylinder surrounding the free end of said plunger tube and slidably between said plunger tube and said guide tube, an outwardly opening check valve between said high pressure cylinder and said low pressure cylinder, means for limiting the movement of said high pressure cylinder relative to said plunger tube, and a coupling member carried by the free end of said high pressure cylinder.

2. A compressor comprising a low pressure cylinder having a discharge conduit including a guide tube communicating with said low pressure cylinder, a plunger mounted within said guide tube, said plunger having a lubricant passageway the outer end of said plunger tube being freely supported in spaced relation to the walls of said guide tube, a high pressure cylinder surrounding the free end of said plunger and slidably between said

plunger and said guide tube, means for limiting the movement of said high pressure cylinder relative to said plunger, and a coupling member carried by the free end of said 5 high pressure cylinder.

3. A lubricant compressor comprising a barrel, compressing means comprising cylinder and plunger elements having relative telescoping movement for receiving lubricant 10 from said barrel and ejecting lubricant under pressure, and separate cylindrical guide means rigid with said barrel for guiding the movement of one of said elements.

4. A lubricant compressor comprising a 15 barrel, compressing means comprising cylinder and plunger elements having relative telescoping movement for receiving lubricant from said barrel and ejecting said lubricant under pressure, and a guide sleeve movable 20 with one of said elements and telescopable with the other of said elements.

5. A lubricant compressor comprising a barrel, means for discharging lubricant from said barrel, compressing means comprising 25 cylinder and plunger elements having relative telescopic movement for receiving lubricant from said barrel and ejecting lubricant under pressure, valve means interposed between said barrel and said compressing means, 30 and guide means rigid with said barrel for guiding the movement of one of said elements.

In witness whereof, I hereunto subscribe my name this 9th day of November, 1921.
